DAVID H. HAYDEN, OF BROOKLYN, NEW YORK

TIE FOR CONCRETE FORMS

Application filed September 10, 1927. Serial No. 218,599.

The invention relates to ties for concrete forms and the like and seeks to provide a simple, inexpensive and efficient tie for holding the walls of concrete forms or molds securely in position and which can be readily applied to the forms and easily disengaged therefrom.

The invention consists in the features hereinafter set forth, illustrated in the preferred form in the accompanying drawing, and more particularly pointed out in the appended claims.

In the drawing, Fig. 1 is a perspective view of a portion of a concrete wall form with one of the improved ties applied thereto.

Fig. 2 is a plan of one of the improved ties, together with portions of the form to which it is applied and with parts shown in section.

Fig. 3 is an enlarged detail view of one end of the tie with parts shown in section.

Fig. 4 is a similar view of the opposite end of the tie.

Fig. 5 is a section on the line 5—5 of Fig. 3.

Fig. 6 is a plan view and Fig. 7 an edge view of a modified form of wedging key for the tie.

As shown in Figs. 1 and 2, the sides of the concrete mold or form are usually formed of wooden boards *a* and over the outer faces of these boards extend vertical uprights *b*. Horizontal braces or whalers *c* extend across and engage the outer faces of the uprights.

The walls of the mold or form are held in position during the pouring and setting of the concrete by interposed spreaders *d* and suitable ties. Preferably, the horizontal braces or whalers *c* are arranged in pairs and the spreaders and ties are arranged at intervals along the lines of the whalers.

Each of the improved ties preferably comprises two wires which may extend through holes formed in the walls *a* and uprights or posts *b*, but which preferably extend between the whalers *c* of each pair and between two of the boards *a*. The form board immediately above the tie wires can be hammered down into sufficiently snug contact with the board

immediately below it to form a sufficiently tight joint.

The ends of each tie are provided with form-clamping collars or abutment members and preferably the two wires are permanently fixed to a collar 11 which forms a head at one end of the tie. Preferably, as shown most clearly in Fig. 4, the wires extend through openings in the head 11 which are slightly larger than the diameters of the wires and the end portions of the wires are then upset to fill these openings and are welded to the head and the outer projecting ends of the wires are riveted over the outer face of the head as shown.

The opposite ends of the wires of the tie extend through an opening or elongated slot 12 of a collar 13 and the ends of the slots are rounded to form seats 14 which snugly fit the wires. Preferably, the opening or slot 12 is formed in the collar by punching and this operation slightly tapers the walls of the slot. Preferably, but not necessarily, the collar is applied to the ends of the wires with the larger end of the slightly tapered slot outermost. The wires are firmly secured to the collar by a wedge or wedging key 15 which is adapted to be driven inwardly through the opening or slot 12 and between and in parallel relation with the wires.

In applying the tie as stated, it is preferably passed between two of the wall boards *a* and between the whalers of each pair. The head 11 and the collar 13 of the tie are preferably thin and flat and are provided with flat inner faces which are adapted to abut against the outer faces of the form structure, or preferably, as shown, against washers 16, which in turn overlap the outer faces of the whalers *c*. These washers are quite large and are square in shape in the form shown and are provided with holes for receiving nails 17 by which the horizontal braces or whalers *c* are held in position. After application, the wires of the tie are drawn tightly to position and, while held taut, the clamping collar 13 is secured to the wires by means of the wedging key. If desired, plain lengths of wire may be employed and the collar or head 11 of the tie similarly secured to the wires by

means of a wedge before the tie is applied to the form.

The wedging key is of considerable length and projects inwardly to some extent beyond the collar 13 and the adjacent washer 16 and also extends outwardly to a considerable distance therefrom so that it can be conveniently driven to position. In order that they may be of sufficient strength, the wires, collars and wedges of the tie are preferably formed of hard steel. The wedges may be in the form of ordinary cut nails having parallel sides and tapered edges. However, as most clearly shown in Fig. 5, the width of the wedge is 10 slightly less than the width of the slot 12 in the collar, so that it will be held by the tie wires 10 out of frictional contact with the collar and capable of exerting its maximum clamping action upon the wires. In the preferred form shown, the key 15, instead of tapering throughout its length, is provided with a tapered or wedge portion 18 only at its inner end. This wedge portion is of slight taper and of such size that it can be readily inserted between the wires. At its butt end, it is of increased taper so that as the wedge is 25 driven home, the wires 10 are compressed between the butt end of the wedge and the seats 14 at the ends of the opening or slot 12 in the collar. Preferably, also, the tapered edges of the wedge portion are provided with 30 grooves or seats 19 which fit the wires and increase the surface contact and the grip of the wedge upon the wires. Also, the wedge is 35 provided with shoulders 20 having inclined grooves or seats for the wires and which are arranged to spread the ends of the wires and bent or offset them over the outer edge of the collar opening. In this way, the ends of the 40 wires are crimped or interlocked with the collar to hold the latter more firmly in position and prevent the spreading of the mold walls. Preferably, also, the edges of the 45 wedging key are provided with recesses 21 between the shoulders 20 and the wedge portion 18 which receive the rounded bends of the wires and into which portions of the wires are slightly offset as the wedge is driven to 50 position to firmly interlock the latter with the wedge. Obviously, with the arrangement shown, strain upon the tie due to the pouring of the concrete will tighten the grip between the wires, collar and wedge.

A modified form of wedging key 15' is 55 shown in Figs. 6 and 7. This form is provided with a wedge portion 18' and inclined shoulders 20', but the recesses between the wedge portion and shoulders are omitted. Preferably, as shown, the edges of the wiring 60 seats 19' in this form, are provided with nicks or notches 22 to form teeth for gripping the wires.

As shown in Figs. 3 and 4, the washer 16 is provided with a circular opening 23 which 65 is slightly less in diameter than the length

of the slot 12 in the collar 13. With this arrangement, slight impressions are formed in the wires by the edge of the washer opening, as the wedge is driven to position, to aid in holding the wires against slipping.

With the improved tie, forms for concrete walls, columns and the like can be quickly constructed. It is not necessary to bore holes in parts of the form structure to receive the ties and the ties will stoutly resist pressure on the mold walls so that the concrete can be rapidly poured. When the concrete has set, the tie wires can be readily cut to permit removal of the form and the wires can be cut off flush with the face of the concrete or withdrawn therefrom as desired. Also, if the wires are left in the concrete, their projecting ends can be readily twisted off by applying a wrench to the tie collars which are preferably square.

Changes may be made in the details set forth without departure from the scope of the invention as defined in the appended claims.

I claim as my invention:

1. A tie for concrete forms comprising a plurality of wires, a clamp collar having an opening through which the ends of the wires extend, and a wedge driven inwardly through the opening and between the wires to secure the clamp collar in adjusted position on the wires, substantially as described.

2. A tie for concrete forms comprising two wires, form clamping collars on the ends of the wires, at least one of said collars being adjustable in position and having an opening through which the ends of the wires extend, and a wedge adapted to be driven inwardly through the opening and between the wires to secure the collar in adjusted position, substantially as described.

3. A tie-bolt for concrete forms and the like comprising a plurality of wires, a clamp collar forming an abutment member for the tie-bolt and having an opening provided with seats for the wires, and a wedging key driven inwardly through the opening and between the wires and held out of frictional contact with the collar by the wires, substantially as described.

4. A tie-bolt for concrete forms and the like comprising a head, two stems or wires fixed to said head, a clamp collar having a slot provided with seats at its ends for the wires, and a wedge adapted to be driven inwardly through said slot and between the wires to clamp the latter in said seats, substantially as described.

5. A tie-bolt for concrete forms and the like comprising two wires, an abutment head at one end, a clamp collar forming an adjustable abutment member at the other end of the tie-bolt, said collar having an opening through which the ends of the wires extend, and a wedging key driven inwardly through

the opening and between the wires, the collar and the key having opposed seats between which the wires are clamped, substantially as described.

5 6. A tie for concrete forms comprising two wires, a head at one end, a clamp collar having an opening through which the opposite ends of the wires extend, a wedge driven inwardly through the opening and between the wires, and washers on the tie for engaging the form structure and against which the head and clamp collar abut, substantially as described.

10 7. A tie for concrete forms comprising two wires, a head at one end, a clamp collar having an opening through which the opposite ends of the wires extend, a wedge driven inwardly through the opening and between the wires, and washers on the tie for engaging the form structure and against which the head and clamp collar abut, said washers having openings for receiving nails that hold the outer braces of the form structure in place, substantially as described.

15 8. A tie for concrete forms and the like comprising a tie-wire, a clamp collar thereon, and a wedge adapted to be driven through the collar in parallel relation with the wire for clamping the latter to the collar, said wedge having a shoulder for bending or offsetting the wire into interlocked relation with the collar as the wedge is driven to position.

20 9. A tie for concrete forms and the like comprising two tie-wires, a clamp collar on said wires and a wedge driven through the collar and between the wires and arranged to offset the wires into clinched or interlocked relation with the collar.

25 10. A tie for concrete forms and the like comprising two or more tie-wires, a clamp collar thereon, and a wedge adapted to be driven inwardly through the collar and between the wires for clamping the latter to the collar, said wedge having shoulders for spreading the wires and bending them over the outer edge of the collar opening, substantially as described.

30 11. A tie for concrete forms and the like comprising a tie-wire, a clamp collar thereon, and a wedge adapted to be driven through the collar in parallel relation with the wire for clamping the latter to the collar, said wedge having a recess into which the wire is offset as the wedge is driven to position, substantially as described.

35 12. A tie for concrete forms and the like comprising two or more tie-wires, a clamp collar thereon, and a wedge adapted to be driven inwardly through the collar and between the wires for clamping the latter to the collar, said wedge having shoulders for bending the wires over the outer edge of the collar opening and recesses adjacent said shoulders for receiving the bends of the wires, substantially as described.

40 13. A tie for concrete forms and the like

comprising two wires, a clamp collar having a slot provided with seats at its ends for the wires, and a key adapted to be driven into the slot between the wires, said key having a wedge portion at its inner end of slight taper but of increasing taper at the butt end to compress the wires between it and the collar seats, substantially as described.

45 14. A tie for concrete forms and the like comprising two wires, a clamp collar having a slot provided with seats at its ends for the wires, and a key adapted to be driven into the slot between the wires, said key having a wedge portion at its inner end of slight taper but of increasing taper at its butt end to compress the wires between it and the collar seats and said key having inclined shoulders for bending the wires over the outer edge of the collar opening and recesses between the shoulders and the wedge portion for receiving the bends of the wires, substantially as described.

50 15. A tie for concrete forms and the like comprising two wires, a collar having a slot through which the ends of the wires extend, a wedge adapted to be driven inwardly through the slot and between the wires to secure the latter to the collar, and a washer on the wires against which the collar abuts, said washer having a circular opening slightly less in diameter than the length of said slot, whereby the washer forms impressions in the wires when the wedge is driven to position, substantially as described.

55 16. A tie for concrete forms comprising a tie-rod, a head fixed to one end of the tie-rod, a collar having a slot provided with a seat at its end for the tie-rod, a wedge of less width than said slot and having parallel sides and tapered edges and adapted to be driven inwardly through the slot to clamp the collar in adjusted position on the rod, the head and collar having flat inner faces arranged to abut against the outer faces of the form structure or of interposed washers, substantially as described.

60 17. A tie for concrete forms, a tie-wire, form-clamping collars on the ends of the tie-wire, at least one of said collars having a slot through which the wire extends, and a wedge of less width than the slot and having parallel sides and tapered edges and adapted to be driven inwardly through the slot to clamp the collar to the wire, the collar and the wedge having opposed seats fitting the wire, substantially as described.

65 18. A tie for concrete forms and the like comprising a head, two stems or wires extending through and riveted to said head, a clamp collar through which the opposite ends of the wires extend, and a wedge adapted to be driven through the collar and between the wires for securing the collar thereto.

70 19. A tie for concrete forms comprising a plurality of tie-wires, a collar forming an abutment head for the tie and having an

opening through which the ends of the wires are inserted and a wedge adapted to be driven inwardly through the opening and between and in parallel relation with the wires for clamping the same to the collar.

20. A tie for concrete forms comprising a plurality of tie-wires, a collar having a wrench-receiving periphery and a non-circular opening through which the wires are inserted, and a wedge extending through the opening and between the wires for clamping the same to the collar.
